INTELLIGENCE TRANSMISSION SYSTEM

Vladimir K. Zworykin, Philadelphia, Pa., assignor
to Radio Corporation of America, a corporation
of Delaware

Application January 4, 1937, Serial No. 119,026

21 Claims. (Cl. 178—5.6)

The present invention relates to television systems and is particularly directed to television systems wherein the pictorial action is transmitted with all accompanying sound indications which occur with and are coordinated with the pictorial representation.

This invention is a continuation in part of my copending application Serial No. 665,098, filed April 8, 1933, and entitled "Intelligence transmission systems".

In sound motion picture work it is customary to produce a film record on which there are a series of pictorial representations intermittently produced with which, and usually adjacent these pictorial representations, there is also a continuous record of the sound which accompanies the pictorial action. Such a sound record may be of various types such, for example, as the variable density or the variable width type recording, or the sound action may appear upon a separate record from which it is mechanically or electrically reproduced. In such a case, however, the reproduction must be accurately coordinated with the film in reproduction so that there is no observable lapse of time between the observation of the action and the hearing of the related sound.

Television, it has been found, is improved to a considerable degree where the observation of the reconstructed image of the object at the point of transmission is accompanied by a series of sound signals which serve to make the visual action more realistic.

It is with a view to producing a television system having characteristics of this general nature that the present invention is developed.

In the prior art, so far as I am aware, frequent endeavors have been made to transmit simultaneously both image and sound signals, as well as signals to synchronize both the image and the sound, but these previous endeavors usually involved transmitting the picture signals upon one carrier frequency and transmitting the sound signals upon another carrier frequency which is separated from the picture signal or television carrier by a predetermined separation, usually at least equal to the frequency separation corresponding to the highest modulation frequency of the television transmitter. According to another system previously suggested in the prior art, as shown for example by Goldsmith et al. Patent No. 1,770,205 assigned to Radio Corporation of America, it has been suggested to transmit the television signals as modulations of one carrier frequency and then to modulate a second carrier frequency by the sound signals and then, in turn,

to modulate the television carrier also by the sound modulated carrier frequency.

The present invention attempts to improve upon these systems of the prior art and has as its principal aim and object that of transmitting both the television and sound signals, as well as any desired synchronizing signals, upon the same carrier frequency so as to avoid thereby the necessity of generating independent carrier frequencies and providing more than a single modulator for modulating the generated carrier by both the television and the sound signals. In this system sight and sound transmission is so interlocked that the presence of one type of signal substantially assures the presence of the other.

In television transmission the frequency band required to transmit a satisfactory image representation is a function of the number of complete image transmission, that is, the scanning frequency, as well as a function of the number of image points into which each image is assumed to be divided for the purpose of transmission. In transmitting 24 complete image representations per second, for example, which are each assumed to be divided for transmission into 250 elemental strips, each composed of 300 individual elemental areas, for example, it can be seen that the frequency band required approaches 1 megacycle.

When recourse is had to the cathode ray tube as a transmitting and/or receiving instrumentality it is customary to use the cathode ray generated within the tube to scan an object or to reproduce an image of the scanned object for approximately $\frac{1}{2}$ of the time available. This practice originates because of the fact that the cathode ray to scan or to reproduce a picture traverses either the photo sensitive element of the scanning tube or the fluorescent screen of the receiving tube at a relatively slow speed in one direction but at a rapid speed in the other direction so that the scanning or analyzing appears to occur always in one direction. The $\frac{1}{2}$ of the time lost from scanning or reproduction occurs during a reversal of the cathode ray beam from a maximum deflection to a position of "starting" or minimum deflection.

This reversal of the cathode ray has commonly been termed the "return line period" and in this period it is customary to transmit a synchronizing signal by which the synchronizing signal generators or oscillators at both the transmitter and receiver may be locked in step so as to cause the cathode ray beam at both the transmitter and the receiver to operate synchronously. Where the frequency band required is of the order of 54

1 megacycle it is seen that there is, in fact, a loss of substantially 100,000 cycles of intelligence transmission occasioned by the reversal of the cathode ray beam and this full loss cannot be compensated by the inclusion of the synchronous signal within the time period of reversal of the cathode ray, since the synchronizing signal usually requires only substantially $\frac{1}{2}$ of the reversal period for transmission. Hence, it is in this time period which heretofore has been lost, so far as intelligence communication is concerned, that it is proposed to transmit the sound signals which accompany the picture action for each assumed elemental strip of the subject which is reconstructed by the cathode ray at the receiver in its slow transversal from one edge portion to the opposite edge portion of the fluorescent viewing screen.

Therefore, it is an object of the present invention to transmit a combined television and sound indication upon a single carrier modulated sequentially by television and sound signals and, where desirable, also modulated in the time space between the occurrence of the television signals and the sound signals by such synchronizing as may be necessary to frame and synchronize properly the reproduced images.

It is a further object of the present invention to provide ways and means by which sound and television signals may be transmitted upon a single carrier frequency without causing any interfering action one with the other.

It is still a further object of the invention to provide a system for transmitting sound signals related to television image signals in which the sound signals occurring within a relatively long time period may be transmitted within a relatively short time period and then caused to become audible at the points of reception during the same relatively long time period as they occurred at the point of transmission.

It is a further object of this invention to provide ways and means for condensing the sound occurring within the time required to scan a single elemental strip of a subject of which the image is desired and then to transmit in the interval between the periods of transmission of signals representative of the successive elemental strips of the subject this condensed sound record which at the points of reception is again expanded and caused to produce audible signals reproducible simultaneously with the production of the next succeeding series of light values corresponding to the next succeeding elemental strip of the subject of which the image is being produced.

It is a further object of this invention to provide a system wherein a condensed sound record may be produced as a series of electrostatic charges occurring within a relatively long time period and then transmitted in inverse order during a relatively short time period, after which the transmitted sound signals produce at all points of reception a similar electrostatic record in inverse order to that of the sound production and in condensed form from which it is then expanded so as to become audible during a time period corresponding to the time period required for the production of the original electrostatic record from which the sound signals are transmitted.

A further object of the invention is to provide a television system wherein appropriate control means are provided to vary irrespective of the sound signals to be transmitted, the periods of

production of and the transmission of the electrostatic sound indications produced by voice or equivalent modulation.

Further objects and advantages of the invention are to provide a system for transmitting a combined television and sound record which is considerably simplified from the systems at present in use and in which no interference between sound and picture signals can arise; to provide a system which is simple in its construction and arrangement of parts; to provide a system which can be compactly arranged in a receiving instrumentality so as to adapt more easily the system to commercial use; and to provide a system for receiving television and sound signals which can be distributed and sold at retail at a minimum purchase price.

Still other and further objects of the invention will be pointed out in connection with the description of a preferred embodiment of this invention, while many other objects will naturally suggest themselves to those skilled in the art to which the invention is directed by reading the following specification and claims in connection with the accompanying drawings wherein:

Fig. 1 is a graphical representation of the curve plotting the amplitude of the cathode ray deflection with respect to time and represents a single traversal of the cathode ray for example from right to left and left to right;

Fig. 2 illustrates in diagrammatic form a system for storing sound signals as electrostatic charger which later may be utilized to transmit an audible record;

Fig. 3 illustrates in conventional manner a suitable system for transmitting combined television and sound signals;

Fig. 4 illustrates a receiver system for cooperative use with the transmitter shown by Fig. 1;

Fig. 5 illustrates in portion (a) the scanning and return line path of several traversals of either viewing screen of the receiver or light sensitive element of the transmitter, and portion (b) indicates conventionally the signals representative of both picture synchronizing and sound for one single scanning line;

Fig. 6 diagrammatically represents the tube used to store as the electrostatic charges a series of sound signals occurring within the scanning period of a single line of a subject of which the image is being produced, and in this figure the portion (a) represents a top portion looking down upon the tube shown, for example, by Fig. 2, and portion (b) indicates a lower view of the storing elements of the tube of Fig. 2, for example;

Fig. 7 diagrammatically illustrates a wave shaping circuit for producing saw-tooth current for use in the deflecting circuits;

Figs. 8a, 8b and 8c illustrate graphically voltage waves and a current wave as an aid to explaining the operation of the circuit shown in Fig. 7, and

Fig. 9 shows in greater detail one of the embodiments which the system for storing sound illustrated in Fig. 2 may take.

To make reference now to the drawings forming a part of this specification and disclosure, it can be seen, from the showing of Fig. 1, that the time required to produce one single picture line or, in other words the time required to scan one single elemental strip into the subject of which the image is desired is assumed to be divided, can for purposes of illustration be regarded as unity. This time period may then be assumed

to be divided into two distinct portions designated as I and II. During the time period designated as I the curve of amplitude against time is seen to rise from substantially a zero value to 5 a maximum, and during the time period II is seen to return again to a zero value. For purposes of further explanation the time period I has been 10 further identified as "A" and it is during this period that the cathode ray which may be assumed to sweep from the left edge of either the light sensitive element or plate of the transmitter or the fluorescent screen of the receiver. This motion or deflection of the cathode ray pencil or beam occurs at a relatively slow rate. 15 However, as soon as the cathode ray beam reaches its maximum amplitude of swing in one direction it must be returned rapidly to the starting position so as to be prepared to traverse again the photo-sensitive plate of the transmitter or the 20 fluorescent screen of the receiver and it is this portion of the swing or deflection motion of the cathode ray that is identified as the portion II of the curve of Fig. 1. During the period II no pictorial intelligence can be transmitted and 25 therefore, this time period, which amounts substantially to $\frac{1}{6}$ of the total time period available, is lost so far as pictorial intelligence transmission is concerned. It is, therefore, during 30 this time period that it is proposed, according to the present invention, to transmit both the synchronizing and the sound signals. The "return line period" designated as II is, therefore, assumed to be divided into three distinct periods or 35 portions B, C, D. During the periods B and D synchronizing signals serving to synchronize the cathode ray beams at the transmitter and all receiving points may be transmitted, and during the portion C, which otherwise is not utilized for transmission, it is proposed to transmit all of the 40 sound which occurred during the period A which represents the period pictorial intelligence transmission.

If it is assumed that the pictorial subject of which the image is desired is divided into 250 45 elemental strips, for example, and the rate at which complete pictorial representations are transmitted is 24, then it is seen that the total time required to move the cathode ray from a position of zero amplitude to a maximum and 50 back to a zero amplitude is of the order of $\frac{1}{6000}$ of a second and that the time period required to move the cathode ray from a position of maximum to a minimum amplitude is of the order of $\frac{1}{60000}$ of a second. Therefore, it is during this 55 $\frac{1}{60000}$ of a second time period which otherwise cannot be utilized except to transmit the synchronizing signal that the sound signals occurring within the period designated as A or during $\frac{1}{6}$ of each $\frac{1}{6000}$ of a second time period should 60 be transmitted.

If reference is now made to the showing in Fig. 2 sound signals which may be producible either by optically analyzing the sound record portion of a motion picture film record through appropriate 65 light translating elements or which may originate through the mechanical or electrical pick-ups from a phonograph type of record or which may be spoken, for example by the subject being televised, are caused to influence and modulate 70 a microphone 4 which is connected with an appropriate amplifier 3. The output signals from the amplifier 3 are then caused to control and modulate a cathode ray 5 generated within the cathode ray tube 7 so as to control in a manner 75 generally similar to the system for control of

the cathode ray shown and described by patent to Nicolson No. 1,470,696 assigned to Western Electric Company, so as to permit the production of an electrostatic sound record in a manner to be hereinafter described. 5

The cathode ray tube 7 is provided with the usual electron emitting cathode 9, a grid control element 11 and an anode 13. Instead of a fluorescent end wall, as shown by the above mentioned Nicolson patent, the cathode ray tube 7 is 10 provided at its end portion opposite the electron source with a series of storage or condenser elements, generally designated at 15, which will be described more fully as to their construction in connection with the description of Fig. 6. In 15 general it may be stated that the condenser elements 15 are formed from a conducting end plate 17 adjacent to which is a layer of mica or other suitable insulating material 19 to the under side of which is a second conducting plate, generally 20 designated at 21. A carbonized material 23 coats independent sections of the plate 21 so as to form from the metallic layer 21 a member which has sections of different electrical properties so that there is a variance in the emission of secondary electrons over different portions of the 25 plate or electrode area.

If now the cathode ray pencil 5 generated within the cathode ray tube is modulated as suggested by the above named Nicolson patent, by 30 the signals appearing in the output of the amplifier 3 which are connected to the grid and cathode elements 11 and 9 of the tube 7 by way of conductors 25 and 27, the modulated cathode ray pencil will be capable of producing different electrostatic charges upon the individual condenser elements including the plates 17 and 21 separated by the insulating layer 19. These varying 35 charges represent the varying amplitude sound modulation frequencies appearing in the output 40 circuit of amplifier 3 during the scanning period A. As these varying charges are being produced the cathode ray pencil 5 is, according to the showing of Fig. 2, moved from right to left by 45 means of varying voltages applied from a source (not shown here but illustrated in Fig. 3) in accordance with the amplitude-time curve of Fig. 1 to the deflecting plates 29, 29' by way of conductors 31 and 33 of which the latter is grounded at 35 or connected to the cathode element of the 50 tube which is grounded at 35.

Suitable anode potential to cause the cathode ray to be projected from the cathode 9 to the condensers 15 is supplied between the anode element 13 and the cathode 9 by way of a battery 55 or other suitable source 35, which in a commercial installation is usually the well known socket power unit serving to supply all operating voltages from an alternating current source.

Let it now be assumed that the cathode ray pencil 5 is moved from its point of greatest deflection to the left of the position shown in Fig. 2 over to its maximum deflection at the right of Fig. 2, or that voltages have been supplied to the deflecting plates 29, 29' as shown by the portion 65 o, a of the curve I of the curve of Fig. 1 so that the cathode ray is just ready to move rapidly from right to left, or in other words from maximum to minimum deflection, according to the portion of curve of Fig. 1 designated as II. 70

At this time period an appropriate biasing source, to be hereinafter described more fully in connection with Fig. 3, causes the amplifier 3 is biased to cut-off and consequently no sound controlled modulation signals are applied across 75

the grid cathode circuit of the cathode ray tube 1. The cathode ray pencil 5 is consequently free from intensity variations and is, therefore, at "normal" intensity during the period when it sweeps from the right hand portion of the condensers 15 of Fig. 2 over to the left hand portion, and secondly, the charges which have been stored in the various individual capacity elements forming the condenser element 15 are discharged. 5

10 These charges are then applied to the input circuit of amplifier 31. Amplifier 31, during the period when sound modulation frequencies are supplied to the grid-cathode circuit of the cathode ray tube 1 is biased to cut-off by the same 15 variable biasing source now serving to bias the amplifier 3 to cut-off. Therefore, during the period of rapid traversal of the cathode ray across the several condenser elements 15 the sound signals which had been converted into electrostatic charges appear in the output circuit of 20 the amplifier 31 which connects to the modulator of the transmitter (not shown in this figure) in inverse order to that of their production. Thus, the sound signals are amplified and transmitted 25 within a time period substantially no greater than $\frac{1}{2}$ of the time period during which the sounds were produced.

As soon as cathode ray pencil 5 is returned to the plate at the extreme left hand edge portion 30 of the tube 1, looking at Fig. 2, the variable bias source serves to bias the amplifier 31 to cut-off but no longer affects amplifier 3. In this manner, amplifier 3 is again able to supply sound modulated signals to the grid electrode of the cathode ray tube and thus to charge again the various 35 capacity elements to different degrees for the purpose of producing an electrostatic record of the sound originating at the microphone 1 within the time period corresponding to the slow traversal of the cathode ray from left to right, after which the same sequence of events hereinabove mentioned is repeated again and again until the entire picture and sound transmission is complete. 40

45 Reference may now be made to the showing in Fig. 3 of the drawings which illustrates, partly in schematic form, a complete television transmitting system provided with means for transmitting related sound signals. In this arrangement, for convenience of illustration, it has been assumed that a motion picture film 41 is the subject of which the image is desired, although, of course, it is recognized that any type of subject or an indoor or outdoor scene may be substituted for the film without departing from the spirit and scope of this invention. If a film subject 41 is used as the subject from which visual intelligence is to be transmitted, this subject is moved, preferably intermittently, relative to the 50 scanning device, such as the cathode ray tube 43, in the general direction shown by the arrow. Each frame portion of the film subject 41 is illuminated from an intense light source 45, such as an arc or other suitable type, which directs the issuing light therefrom through an appropriate optical system 47 through to the film. In accordance with the varying transparency of the film light of proportionately controlled intensity is directed by means of a second optical system 48, which is usually formed from a plurality of individual lens elements, so as to be focused upon the light sensitive electrode or plate 51 contained within the scanning tube 43. The scanning tube in the form herein illustrated 55 may be of the same general construction as was

shown and described in my co-pending application Serial No. 574,772 filed November 13, 1931 and assigned to Radio Corporation of America (Docket #2000) wherein there is disclosed the screen structure 48 in the form of an insulating sheet upon one side of which is a thin conducting film 50 and upon the other side of which is a uniformly distributed series of individual photosensitive elements 51. These photosensitive elements may, where desired, be formed in the manner disclosed by Sanford F. Essig in application Serial No. 594,779 filed February 24, 1932 (Docket RCA Victor 2059) and assigned to Radio Corporation of America. 10

15 Within the scanning tube 43 there is generated by means of the co-operative action of a cathode 53 and an anode 55 a cathode ray pencil 57 which is adapted, when suitably deflected in a vertical plane by the electrostatic deflecting plates 59 and 59' and in a horizontal path by the electromagnetic deflecting coils 61 and 61', to sweep the entire area of the light sensitive plate 51. Whenever light from the film is projected upon elemental areas or sections of the light sensitive electrode or plate 51 the individual elements thereof 20 emit electrons and take on positive charges corresponding in value to the light intensities to which they are subjected. Thus, an electrical image of the subject or object is developed over the surface of the screen structure. 25

30 In order to utilize the electrical image to reproduce at a receiving station the electrostatic charges referred to are neutralized or discharged successively by causing the cathode ray pencil 57, to scan the photosensitive surface 51 under 35 the influence of the electrostatic deflecting field produced between the deflecting plates 59 and 59' and by the electromagnetic deflecting field produced by the coils 61 and 61'. 35

40 For the purpose of removing the electrons of the ray pencil 57 which are not required to neutralize the respective positive charges accumulated by the individual photosensitive elements 15, as well as the electrons emitted by these elements in taking on these charges, a suitable collector or anode 63, in the form of a screen, is supported in the proximity to the photosensitive surface of the screen structure and is maintained at a positive voltage through conductor 73 connecting to a suitable source 77, leading to ground 45 at 61', as shown. 50

45 The successive discharges of the positive charges upon the individual elements 51, as explained, causes corresponding current impulses or picture signals to be developed across the resistor 63 in the grid or input circuit of a suitable picture signal amplifier 85, for which purpose the platinum film 50 is connected to this circuit by a conductor 69 and one of the wire supports 52 carrying the screen structure 40. 60

65 The synchronizing signals for deflecting the cathode ray pencil 57 in a horizontal direction are generated in a synchronizing signal generator 77 which generates a wave of the saw-tooth type substantially as shown by Fig. 1. These signals are supplied to the horizontal deflecting coils 61 and 61' by way of the conductors 79 and 79' and the shaping circuit 179. Similarly, the vertical synchronizing or framing signals which cause the cathode ray pencil to move in a vertical direction are generated in a similar synchronizing signal generator 81 but of a lower frequency, usually of the order of 24 cycles, assuming 24 complete image transmissions are to be made per second, and are then supplied to the deflecting 70 75

plates 59 and 59' by way of conductors 83 and 83'.

The vertical sweep voltage may be applied to the deflecting plates as illustrated, or may be applied through deflecting coils such as is used for the horizontal sweep circuit. As a matter of practice, however, since no difficulties are encountered at low frequencies in using electrostatic deflection, it is simpler to use such deflections for the vertical sweep as has been illustrated. At the higher frequencies, however, difficulty arises in that the deflecting electrodes constitute a condenser and the upper harmonics present in a saw-tooth wave are of such high frequency that the impedance of the condenser represented by the deflecting plates 151 virtually short circuit these components and destroy the linearity of the sweep voltage with respect to time.

Accordingly, electromagnetic coils through which a suitable voltage wave may be applied is desirable. It should be understood, of course, that to apply a saw-tooth voltage wave to such coils would also result in distortion since the impedance of the coils at high frequencies discriminates against high frequency current components. To overcome this difficulty, the saw-tooth wave is passed through a wave shaping circuit 179 which predistorts the voltage wave so that when the distorted voltage wave is applied to the deflecting coils a true saw-tooth current wave results. The saw-tooth current wave, therefore, produces an electromagnetic field which builds up linearly with time. Such a wave shaping circuit is shown in Fig. 7 and is in form of the same type of circuit described in considerable detail in an application numbered 544,959 by Arthur W. Vance, entitled "Intelligence transmission systems", which application was filed June 17, 1931 and upon which application a British Patent No. 395,499 has been issued on July 30, 1933.

Referring now to Fig. 7, a saw-tooth wave as shown in Fig. 8a is applied to the input of the wave shaping circuit 179 across the resistor 205. This wave is amplified by the triode 201 and across the plate circuit of this tube there appears a voltage wave shown in Fig. 8b. The inductance 207 may be of the order of 100 henrys or more, so that it acts substantially as open circuit for the alternating current components but permits the D. C. plate current to be maintained constant. Connected in parallel with the inductance 207 is serially connected resistor 209 and condenser 211. The grid of the tube 203 is connected to the serially connected resistor and by suitable adjustment of the movable tap on the resistor 209 the proper wave shown in Fig. 8b can be obtained. This voltage wave is linearly amplified by the tube 203 and the constance of the choke 213 and the condenser 215 are so chosen as to present a voltage wave across the terminals 217 which is substantially proportional to the voltage wave shown in Fig. 8b. This voltage wave applied to deflecting coils, for example, 161 and 163, then produces a saw-tooth current wave as illustrated in Fig. 8c. From the terminals 217 leads are likewise brought down to the amplifier bias source 129 for the reasons as will be pointed out more fully below. It will be understood that in accordance with the teachings of the Vance application and patent, the condenser 211 may have substituted for it an inductance, the choice being merely one of convenience.

The frequency of the horizontal synchronizing signals is equal to the number of elemental strips into which each image representation is assumed to be divided for purposes of analysis multiplied

by the number of complete image representations per second.

As varying voltage drops are produced across the resistor 65 so as to represent the varying light values reaching the light sensitive element 51 various potentials on the control grid of the amplifier tube 85 produce proportionate output currents which are then transferred to a second amplifier 87, usually a multistage amplifier, whose output is connected to the modulator 89. 10 The oscillator 91 serves to generate the carrier frequency and connects with the modulator 89 which is in turn connected with the transmitter amplifier 93 from which the energy output is transmitted to various points of reception either 15 by way of a radio transmission link from the antenna 95 or by way of a wire line transmission link, where it is desired to send the television signals over a wire line.

As was explained above in connection with 20 Fig. 2, sound signals may be supplied directly to the microphone 4 or may be translated from the film record 41 which is being explored for image transmission purposes. The sound signals there converted by the microphone or photocell into 25 electrical signals are then supplied to the sound signal amplifier 3. As was also explained in connection with Fig. 2, there sound signals appear across the grid cathode circuit of the cathode ray tube 7 and serve to modulate the generated 30 cathode ray pencil 5 within this tube. The output signals which are produced from the electrostatic charges formed in the condenser elements 15 are supplied to the amplifier 37. To each of the amplifiers 3 and 37 there is connected 35 an amplifier biasing source 97 controlled from the synchronizing signal generator 77 for horizontal deflection of the cathode ray pencil which serves alternately to bias amplifiers 3 and 37 to cut-off. The amplifier biasing source 97 may 40 be, for example, the device shown in co-pending application of H. Branson, Serial No. 644,417, filed November 26, 1932, and entitled "Amplifiers" on the basis of which application British Patent No. 415,619 was accepted August 30, 1934, or the circuit shown and described in the Branson British Patent No. 834,891, accepted September 11, 1935, or the Shore Patent No. 2,005,111 issued June 18, 1935, and entitled "Amplifiers".

It is desirable to maintain cut-off bias on amplifier 31 for a relatively long time period, or in 50 other words for a time period represented by the time period I of Fig. 1, and during this same time period I the amplifier 3 should be maintained in an operative state, whereas for the 55 time period II (see Fig. 1) the amplifier 3 for sound signals should be rendered inoperative, or in other words biased to cut-off, whereas amplifier 37 should be operative. To produce this result the biasing action produced from the bias source 97 and effective upon amplifiers 3 and 37 changes in accordance with the rate or frequency 60 of the synchronizing signals generated so that the amplifiers 3 and 37 are rendered alternately 65 operative and inoperative for time periods corresponding to the above enumerated conditions.

The operation of the bias amplifier 97 will now be described in detail. Referring now to Fig. 9, there has been shown in detail the conventional amplifiers for the microphone and for the sound channels 3 and 37 respectively together with the bias amplifier 97 which, for purposes of illustration, is shown as the type of amplifier disclosed in the Shore Patent No. 2,005,111 referred to above. A voltage wave having the shape shown 75

in Fig. 8b is derived from the output of the wave shaping circuit 179 and fed to the input terminals 219. The tube 221 is normally biased to cut off by the battery 223 so that there appears across the plate resistance 225 no voltage drop. The plate resistor 225 is also made part of the cathode grid circuit of tube 237 of the amplifier 37 and under such conditions, voltages applied to the terminals 239 are linearly amplified 10 through the tubes 237 and 238, the output of which is fed to the modulator of the transmitter. The tube 231 has its grid connected to the plate resistor 225 and is biased by the battery 233 to an appropriate value so that current normally flows 15 through the plate resistor 235, under the conditions of tube 221 being biased to cut-off. The voltage drop across the resistor 235 is fed to the tube 227, in its cathode grid circuit, and in such polarity as to bias the tube 227 to cut-off and 20 of such magnitude that any signal voltage applied from the microphone is insufficient to actuate the amplifier. A condenser 240 is connected from the plate resistor 235 to the grid of the tube 221 in accordance with the teachings of the 25 Shore patent, referred to above. When the voltage wave of the form shown in Fig. 8b is applied to the terminals 219 current begins to flow in the plate circuit 225 of the tube 221, producing a voltage drop, which is then amplified by the 30 tube 231 and a portion of the energy fed back as positive regeneration to the input circuit of the tube 221, which process repeats until saturation current flows in the tube 221, under which conditions, tube 231 has so much negative voltage 35 applied between its grid and cathode by virtue of the voltage drop through the resistor 225 taking place, due to current flowing through tube 221, that the tube is cut off so that no plate current flows through the resistor 235. Under these 40 conditions the voltage drop across the resistor 225 is now sufficient to cut off the tube 237 so that there is no longer any voltage fed to the modulator of the transmitter. At the same time, since there is no plate current flowing through the 45 resistor 235, tube 227 is biased linearly by the battery 228 and signal voltage obtained from the microphone is linearly amplified and has its output passed on to the elements 11 and 9 of tube 7. When the linearly increasing portion of the wave 50 shown in Fig. 8b ceases, and the abrupt collapse takes place, the operation of tubes 221 and 231 are reversed, since the tube 221 goes back to its cut off condition and the tube 231 begins to draw current. Under these conditions then, the 55 amplifier 3 is rendered inoperative, and the amplifier 37 is rendered operative. It will thus be observed that the microphone amplifier is operative during a relatively long period and the amplifier 37 operative only during a short period. 60 The horizontal synchronizing signal generator 17 which serves to move the cathode ray pencil 57 transversely in the scanning tube 43 is also connected by way of conductors 31 to the deflecting plates 29 and 29' of the tube 7 so as to 65 cause the generated cathode ray pencil 5 to move back and forth across the tube in an appropriate manner.

The sound signal amplifier 37 connects with 70 the modulator 89 so that the amplified sound signals serve also to modulate in modulator 89 the generated carrier frequency as generated by the oscillator 91. The sound modulated carrier frequency signals are likewise suitably amplified 75 in the transmitter amplifier 93 and transmitted

from the antenna 95 or by way of a suitable wire line connection to all receiving points.

If the synchronizing signals are generated in the generators 11 and 81 are supplied to the modulator 89 in such manner as to be 180° out 5 of phase with the picture signals transmitted to the modulator 89 by the amplifier 87 and the sound signals transmitted to the modulator 89 by the amplifier 37 the synchronizing signals will correspond substantially to black signals, as has 10 already been disclosed in the co-pending application of R. D. Kell, Serial No. 565,953 filed September 30, 1931 and assigned to Radio Corporation of America (Docket #1607).

In this manner the signals which are transmitted 15 from the transmitter amplifier 93 follows the following sequence:—first, picture modulated signals which occur during a relatively long period of time designated as time period A; second, synchronizing signals occurring during 20 a relatively short period of time designated as time period B; third, sound signals which also occur during a relatively short period designated by the time period C; and then fourth, where necessary, a second synchronizing signal occurring 25 during a short period of time designated as D.

The signals thus transmitted may then be received by any suitable form of receiving device as suggested by Fig. 4. Where the transmission is 30 by radio the signals may be received upon the antenna system 97 and suitably amplified and detected in a receiver detector amplifier 99 to which the output of the local oscillator 101 is supplied. The resulting intermediate frequencies 35 are then amplified in the intermediate frequency amplifier 103 from which the sound signals may be detected by the detector 105 and from which the picture and synchronizing signals may be detected in the detector 107.

The sound signals detected in detector 105 are then suitably amplified by the amplifier 109 and are supplied to the cathode ray tube 111 across the grid and cathode elements 113 and 115 respectively so that the cathode ray pencil 117 passing 45 beyond the anode 119 is controlled in intensity in proportion to the received sound signals. This intensity controlled cathode ray pencil 117, which is synchronized in its motion with the cathode ray pencil 5 of the tube 7, then charges a series of 50 capacity elements generally designated 121 during its rapid sweep or deflection path from right to left to degrees proportionate to the received sound transmitted within the time period C shown by Fig. 1. In this manner an electrostatic 55 record of the received sound signals is produced upon the capacity elements 121 and later, as will herein be pointed out, this electrostatic sound record may be utilized in inverse order to that of its production to cause at each receiving point 60 an audible record of the sound which influenced the microphone or other form of pick-up device 1 at the point of transmission.

This is made possible by causing the cathode ray pencil 117 to be swept back and forth from right to left and left to right over the capacity elements 121 by supplying varying voltages to the deflecting plates 123 and 123' from the source of horizontal synchronizing signals as generated in the synchronizing signal generator 125. These controlling voltages are conveyed to the deflecting plates of the tube 11 by way of conductors 127 and 127' so that the cathode ray pencil 117 in the tube 11 is synchronized properly with the 75

cathode ray pencil 149 of the viewing tube to be hereinafter described.

As was pointed out in connection with the description of Figs. 2 and 3, the sound signal amplifier was alternately biased to cut-off and rendered operative by signals originating in an amplifier biasing source 97. Likewise, in the receiver these same conditions must occur. The amplifier biasing source 129 which connects with the sound amplifier 109 by conductors 131 and 131' is controlled, in a manner similar to the amplifier biasing source 97 of Fig. 3, by the horizontal synchronizing signal generator 125 so that during the time period of rapid motion of the cathode ray pencil 117 within the tube 111 the input sound signal amplifier 109 may be rendered operative and during the slow motion period, corresponding to the time period I of Fig. 1, the amplifier 109 is biased to cut-off or rendered inoperative. It will be noticed that the time period of operation of the input sound signal amplifier 109 thus corresponds to the time period of operation of the sound output signal amplifier 37 of Fig. 3 and that the time period of inoperativeness of the amplifier 109 corresponds to the period of inoperativeness of the amplifier 3 of Figs. 2 and 3.

As the cathode ray pencil 117 sweeps across the capacity elements 121 of the tube 111 from right to left the amplifier 109 is operative. In this way the cathode ray pencil 117 is modulated by the signals received and the capacity elements are charged to different degrees proportionate to the sound to be reproduced. During the period when the cathode ray pencil 117 is reversed in direction so that it sweeps slowly across the capacity elements 121 of the tube 111 the amplifier 109 is inoperative from the amplifier bias source 129, and thus no sound signals can be supplied across the grid cathode circuit 113 and 115 of the tube 111 which means that the cathode ray pencil 117 is not variably controlled as to intensity but is, in other words, at full intensity. At this time period the full intensity uncontrolled intensity cathode ray pencil 117, which is now assumed to be moving from left to right within the tube 111 will serve to discharge the sound signal charges stored on the capacity elements 121. These discharge signals are then supplied to the sound signal amplifier 133 which is now rendered operative by the amplifier biasing source 129 connected thereto by way of conductors 135 and 135'. The amplified sound signals which appear in the output circuit of the amplifier 133 are now rendered audible by the sound reproducer 137. This period of audibility since it occurs during the time period designated by I in Fig. 1 corresponds to the period of operativeness of the cathode ray pencil within the picture reproducing tube, to be hereinafter described. The relatively long time period of operativeness of the sound reproducer 137 coordinates the reproduced sound with the reproduced picture and, at the same time, the manner of reproduction produces a reversal and expansion in time of the received sound signals so that the sound instead of being heard during the short time period at which it is recorded electrostatically within the tube 111, becomes audible during a relatively long time period and in an order, of course, corresponding to the order of occurrence or pick-up at the microphone 1 of Figs. 2 and 3. So arranged, it can be seen that the sound as it becomes audible is delayed by a time period corresponding to that of scanning a single elemental strip of the picture, or in other words, if the sound occurred dur-

ing the period I of the scanning cycle designated in Fig. 1 and was transmitted during the time period II of the same scanning cycle, it will become audible during a similar period I' of the following scanning cycle. This delay will be unobserved because the human ear is not sufficiently sensitive to detect such a small time delay in the sound reproduction with respect to the picture action. In fact, it has been noted that the human ear is usually substantially insensitive to time delays of as much as $\frac{1}{10}$ of a second. In the present system the time delay of the reproduced sound according to the above assumed conditions may occur with a delay of as little as $\frac{1}{6000}$ of a second with a maximum delay period of one scanning cycle plus the $\frac{1}{6000}$ of a second time period.

To reproduce now the picture portion of the transmitted intelligence, the picture signals which have been detected in the detector 107 after suitable amplification in the intermediate frequency amplifier 103 are again amplified to a still further degree in the picture and synchronizing signal amplifier 141. So amplified these signals are impressed across the control circuit of the cathode ray image reconstructing tube 143 which includes the grid or control electrode 145 and the cathode 147. The cathode ray 149 which is generated by the cathode element is then projected through a suitable tubular or equivalent shaped anode member 151 to which a suitable operating voltage relative to the cathode is supplied by way of a battery 153 or directly from the socket power unit. In order to provide for sharply focusing the cathode ray pencil 149 upon the fluorescent end wall 155 of the tube 143, I have herein shown a system whereby the beam may be focused electrostatically as has already been disclosed in my copending application Serial No. 407,652, filed November 16, 1929, assigned to Westinghouse Electric & Mfg. Co., (Docket 14,718) and also which has been disclosed by pending applications of Pierre E. L. Chevallier, Serial Nos. 489,957 and 630,397 filed respectively on October 20, 1930 and August 25, 1932, assigned to Radio Corporation of America, (Dockets Nos. 5860 and 6753).

This focusing action upon the generated cathode ray pencil is provided for by arranging a second anode member 157 upon the inner tube wall and applying to the anode 157 (from a source of voltage 159 or directly from the socket power unit) a voltage of the order of four times that applied to the anode member 151. The second anode member 157 extends from the cone-shaped portion of the tube inwardly toward the neck of the tube in the form of a conducting coating so that between the inner end of the second anode 157 and the anode 151 an electrostatic field is produced which tends to confine the electrons forming the cathode ray pencil to a sharply defined spot upon the fluorescent screen 155. At the same time the higher voltage upon the second anode 157 causes an acceleration of the electron stream after it has been deflected, for example, in a horizontal path by the deflecting coils 161 and 163, which causes the cathode ray pencil 149 to strike the fluorescent end wall of the tube with increased velocity as it sweeps the end wall from left to right and right to left for example. Suitable deflecting currents are applied to the deflecting coils 161 and 163 from the horizontal synchronizing signal generator source 125 which is locked in step with a similar generator at the transmitter upon each receipt of a

synchronizing signal impulse from the transmitter in accordance with the disclosure set forth in the above mentioned application of R. D. Kell.

5 Similarly, the cathode ray pencil is caused to move in a vertical direction, or in other words, up and down across the screen 155, looking at Fig. 4, by means of the vertical deflecting coils 165 which are connected with the vertical synchronizing signal generating source 167 to which is supplied the vertical synchronizing or framing signal transmitted from the point of transmission. The vertical synchronizing signal impulse serves to synchronize or frame the received image signals in a manner which has also been described and claimed in the above mentioned application of R. D. Kell.

As image signals transmitted from the transmitter 95 within the time period I, as shown by the curve of Fig. 1 are received so as to be converted into visible indications the cathode ray pencil 149 of the receiving or viewing tube 143 is simultaneously controlled as to intensity by means of the grid control 145, which preferably operates in accordance with the teachings of the above mentioned Nicolson Patent No. 1,470,696, and controlled as to both the vertical and horizontal position at which it impinges upon the screen 155 by means of the deflecting coils 165, 161 and 163 so that an observer viewing the fluorescent screen 155 of the cathode ray image reproducing tube 143 from the direction shown by the arrow of Fig. 4 will observe light spots having varying intensities which correspond to the varying intensities of light and shadow on similarly coordinated elemental areas of the subject of which the image is to be produced.

The cathode ray tube 143 and the coordinated sound reproducer 137 may, where desired, be mounted within an appropriate cabinet, as has been disclosed and claimed in my previously granted U. S. Patent #1,870,702, with which arrangement it is possible to view the reconstructed image throughout a wide angle by observing the image in the lid of the cabinet within which the television image reconstructing tube and the sound reproducer are located.

By portion (a) Fig. 5 I have shown a portion of the fluorescent screen 155 and thereon have indicated by the solid lines M the paths traced by intensity controlled cathode rays, and by the dotted paths S the interruption period in the produced ray which occurs during the return line period. The synchronizing signals, which, as above stated, assume the characteristics of maximum black signals, cause, when they influence or act upon the control grid 145 of the image reconstructing tube 143, a complete absence or blocking of the cathode ray pencil so that the fluorescent screen during the return line period is uninfluenced by the cathode ray and no resulting light spot appears. By the portion (b) of Fig. 5 there is represented in conventional manner the wave form which may be transmitted throughout any one line scanning cycle. By this figure, portion I indicates the visual signals, whereas portion II indicates the synchronizing and sound signals.

In Fig. 6 there is shown in more detail the storing arrangement of the sound signals in tubes 7 and 111. From Fig. 6a, which may be considered as constituting a view looking down on the top of the tube, it can be seen that the end portion of the tube is formed from a conducting plate 17 adjacent to which and imme-

diate beneath which is an insulating plate or strip of mica or equivalent 19. Immediately beneath the mica layer is the plate member 21 forming the other plate of the condenser 15. The plate member 21 is divided into three distinct sections by appropriately carbonizing separated areas 23 thereof. These carbonized areas are designated in Fig. 6b as the shaded areas 23 whereas the non-carbonized areas 21 are unshaded. With this arrangement the different sections 21 and 23 have different properties so far as the emission of secondary electrons is concerned and, therefore, during the sweep path of the reversal of the cathode ray covers the various sections of the tube in the directions indicated by the arrows adjacent Fig. 6b different intensity electrostatic charges produced upon the various condenser elements may be utilized for transmission.

Having described my invention, what I claim is:

1. The method of communicating intelligence which comprises electrostatically storing a series of electrical energy representations of the intelligence to be communicated during a relatively long time period and scanning the stored electrical energy charges in inverse order to that of their production subsequent to the period of storing and during a relatively short period of time for transmission, the periods of storing and transmitting being of the order of at least six to one.

2. The method claimed in the preceding claim which includes, in addition, the step of repeating the storing and transmission periods at a rate substantially equal to the rate of scanning each elemental strip of a subject for image transmission to reproduce the entire image at a repetition frequency at least equal to the frequency of persistence of vision.

3. The method of transmitting intelligence which comprises producing a series of electrostatic charges each of values proportional to produced intelligence signals and utilizing an electron beam to apply the electrostatic charges to a transmission channel in inverse order to that of their production and during a time period substantially less than the time period of their production.

4. The method of communicating intelligence which comprises storing a series of electrostatic representations of the intelligence to be communicated and subsequently controlling an electron beam by the electrostatic charges for transmitting electrical energy modulated in accordance with variations in the stored energy to utilization points in inverse order to that of its production.

5. The method of communicating intelligence which comprises producing a series of variable electrostatic charges representative of a message to be communicated during a relative long time period and controlling an electron beam by the electrostatic charges for transmitting signals modulated in proportion to variations in the stored electrical energy and in inverse order to that of the production of the stored energy subsequent to the period of storing and during a relatively short time period, the ratio of the periods of storing and transmitting being of the order of at least nine to one.

6. The method claimed in the preceding claim which includes, in addition, the step of sequentially repeating the production of the electrostatic charges in an order inverse to that of the

transmission thereof and at a repetition rate of scanning each elemental strip of a subject for image transmission to reproduce the entire image at a repetition frequency at least equal to the 5 frequency of the order of 24.

7. The method of receiving transmitted intelligence signals which comprises receiving during a relatively short time period a series of sound signals in inverse order to that of generation, 10 producing an electric non-visible electrostatic record of the received intelligence signals in the order of reception, and controlling a cathode ray pencil to produce from the electrostatic sound record in inverse order to that of its production 15 electrical signal energy, and then converting the produced electrical signal energy into an audible record of the sound originating at the point of transmission of the signals.

8. In a system for transmitting intelligence, 20 the method which comprises producing from a series of sound signals a series of electrostatic charges proportional to differential portions of the entire series of generated sound signals, controlling a cathode ray by the electrostatic signals 25 to apply the signals to a transmission channel in inverse order to that of production and during a time period of the order of one-ninth of the period during which the electrostatic signals were produced, receiving the signals applied to 30 the transmission channel, producing from the received signals a series of electrostatic records representative of the generated intelligence and in inverse order to that of its production, controlling a cathode ray beam so as to produce electrical signal energy representative of the received 35 electrostatic records in inverse order to their production and at a rate of the order of nine times slower than that of their production and translating the produced energy into audible intelligence.

9. A system for receiving intelligence signals transmitted in reverse order to that of production which comprises means for receiving during a relatively short time period a series of signals representative of the intelligence signals developed within a relatively long time interval 45 but in inverse order to that of the generation of the intelligence signal, means for producing an electrostatic record of the received intelligence signals in the order of reception, and an electrical 50 commutating means for producing from the electrostatic intelligence signals record in inverse order to that of its production and audible record of the intelligence signals originating at the 55 point of transmission of the signals.

10. In a system for transmitting intelligence, a source of sound signals, means for producing from the series of intelligence signals a series of electrostatic charges of values proportional to the 50 generated intelligence signals, a transmission channel, electrically operating distributing means for applying the electrostatic charges to the transmission channel to produce a series of signals representative of the electrostatic charges, said signals occurring in inverse order to that of production of the charges and active during a time period at least no greater than one-ninth of the period during which the electrostatic charges were produced, means for receiving the signals applied to the transmission channel, means for producing from the received signals a series of electrostatic signal records representative of the generated sound and in inverse order to that of its production, and electrically operative distributing 55 means for causing the electrostatic record pro-

duced at the receiver means to become audible in inverse order to its production and at a rate at least nine times slower than that of its production.

11. The method of transmitting and receiving television image signals and related intelligence signals transmitted upon a single carrier frequency which comprises converting a series of light values from a subject into proportional electric current values, generating a carrier current, 10 modulating the generated carrier by the produced electric currents, simultaneously converting intelligence signals accompanying the representation of which the image is desired into a series of proportional electrostatic charges, simultaneously 15 interrupting the image signal modulation of the carrier and modulating the generated carrier by the produced electrostatic signals in inverse order to that of production during a time period of the order of one-ninth the period of initial modulation by the image signals, repeating the sequence 20 of each independent and separate modulation of the generated carrier at a rate per second at least equal to the highest intelligence frequency to be transmitted, receiving the modulated signals, 25 producing from the image modulated received signal a series of light intensities representative of the various light values of the subject at the point of transmission, interrupting the production of light values at time periods corresponding to the 30 time periods of interruption of the light modulation at the point of transmission, producing during the period of light modulation interruption a series of electrostatic charges representative of sound in the order corresponding to the order of 35 transmission and of an intensity proportionate to the intelligence signals at the point of transmission, repeating the production of varying light values from received signals at a rate corresponding to the repetition rate of transmission, and producing during each repetition of light values 40 an audible indication of the intelligence signals related to the next previously produced series of light values and for a time period identical to that required to produce each series of light values.

12. The method of sequentially transmitting 45 and simultaneously reproducing a plurality of independent intelligence signals which comprise the produced electrostatic signals in inverse order to that of production during a time period which is a fractional part only of the period of modulating the generated carrier by the produced electric current values, simultaneously converting the second of the signals into a series of proportional electrostatic charges, simultaneously interrupting the carrier modulation by the first signals 55 and modulating the generated carrier by all of the produced electrostatic signals in inverse order to that of production during a time period which is a fractional part of the period of modulation by the first series of signals, repeating the sequence of each independent and separate modulation of the generated carrier at a rate per second at least equal to the repetition frequency rate of persistence of vision, receiving the modulated signals, producing from one of the modulated received signals a series of responses 60 representative of the first series of signals originating at the point of transmission, interrupting the production of receiver response indications 65 representative of the first series of signals at time periods corresponding to the time periods of interruption of carrier modulation by the first signals at the point of transmission, producing during the period of interruption a series of elec- 70

- 5 trostatic charges representative of sound in the order corresponding to the order of transmission and of an intensity proportional to the intelligence signals at the point of transmission, repeating the production of varying light values from received signals at a rate corresponding to the repetition rate of transmission, and producing during each repetition of light values an audible indication of the intelligence related to 10 the next previously produced series of light values and for a time period identical to that required to produce each series of light values.
13. A system for communicating intelligence between a plurality of points which comprises 15 means for electrically storing energy representative of the intelligence to be communicated and commutating means for subsequently transmitting the stored electrical energy to utilization points in inverse order to that of its production and prior to the production of subsequent electrostatic charges.
14. A system for communicating intelligence which comprises means for producing a series of 20 electrically stored energy indications representative of the intelligence to be communicated during a relatively long time period and means for reconverting the stored electrical energy into a series of electrical waves representing, in inverse order, the original intelligence subsequent 25 to the period of storing and means for repeating the operations continuously during relatively short periods of time of the order of the period of persistence of vision, the alternate periods of energy storing and re-conversion being of the order of nine to one.
15. In a system for transmitting sound energy, means for producing a series of electrostatic charges of values individually proportionate to 30 instantaneously produced sound signals and a cathode ray device for neutralizing each of the electrostatic charges produced and thereby applying a signal representative thereof to a transmission channel in inverse order to that of their production and during a time period of the order 35 of one-ninth that of the period of their production.
16. The system claimed in the preceding claim which includes, in addition, means for sequentially repeating the alternate production of the electrostatic charges and the neutralization thereof at a repetition rate per second of the order of 24.
17. A system for reconverting transmitted signals distributed during short time intervals into 40 audible signals of apparent long duration which comprises means for receiving during continually interrupted relatively short time periods a series of signals representative of intelligence effects in inverse order to that of generation, means for producing from the received signals an electrical non-visible record of the received signals in the same order of reproduction as the order of reception, and cathode ray means for producing from the electrical record formed an 45 audible record of an order of occurrence inverse to that in which the electrical record is produced so as to represent the intelligence originating at the point of transmission of the signals.
18. In a system for transmitting intelligence 50 signals, means for producing from a series of sound originating at a source an electrostatic record of intensity proportionate to the generated sound signals, a cathode ray for applying the electrostatic signals to a transmission channel in inverse order to that of production and during a time period of the order of one-ninth the period during which the electrostatic charges were produced, means for receiving the signals applied to the transmission channel, means for producing from the received signals a series of electrostatic 55 recordings representative of the initially produced sound and in inverse order to that of their production, and electrically operating distributing means for converting the second-named electrostatic record into a series of audible signals in inverse order to the production of the electrostatic charges and at a rate of the order of nine times slower than the rate of production.
19. The system claimed in the preceding claim which includes, in addition, means at the point 60 of transmission to render the electrostatic record producing means and the electrostatic record converting means alternately operative.
20. In a system for transmitting television image signals and related intelligence signals upon a single carrier frequency, means for converting a series of light values into proportional electric current values, means for generating a carrier current for transmission, means for modulating the generated carrier by the produced electric picture currents, means for simultaneously converting intelligence signals accompanying the pictorial representation of which the image is desired into a series of proportional electrostatic charges, cathode ray means for causing the generated carrier to be modulated by all of the produced electrostatic signals in inverse order to that of the actual time of production, means for sequentially controlling the modulation so that the carrier frequency modulation is controlled 40 at any instant by one of the produced signals only and the duration of each control period corresponds to periods of picture scanning and interruption.
21. A receiving system for receiving signals transmitted in accordance with claim 20 which comprises means for receiving modulated pictorial and intelligence signals, means for producing from the pictorially modulated received signals a series of light intensities representative 45 of the light values at the point of transmission, means for interrupting the production of light values of time periods corresponding to the time periods of interruption of the light modulation at the point of transmission, a cathode ray device for producing during the period of light modulation interruption a series of electrostatic charges representative of intelligence in the order corresponding to the order of transmission and of an intensity proportional to the intelligence 50 signals at the point of transmission, means for causing a repetition of the production of varying light values and of stored intelligence indications from received signals at a rate corresponding to the repetition rate of transmission, and means for producing during the entire period of each repetition of light values an audible 55 indication of the sound related to the next previously produced series of light values.
